UNITED STATES PATENT OFFICE.

FRANK M. HALE AND FLOYD C. McLAUGHLIN, OF KENT, OHIO.

DESIGN FOR A TIRE.

52,055.

Specification for Design.

Patented May 28, 1918.

Application filed October 31, 1917. Serial No. 199,588. Term of patent 14 years.

To all whom it may concern:

Be it known that we, FRANK M. HALE and FLOYD C. McLAUGHLIN, both citizens of the United States, and residents of Kent, in the county of Portage and State of Ohio, have invented a new, original, and ornamental Design for a Tire.

Reference is to be had to the accompanying drawings in which—

Figure 1 is a side view of a tire embodying our new design;

Fig. 2 is a top view thereof;
Fig. 3 is a side view on an enlarged scale of a fragment of the tire embodying our said design.

We claim:
The ornamental design for a tire, as shown.

FRANK M. HALE.
FLOYD C. McLAUGHLIN.
